UNITED STATES PATENT OFFICE.

HENRY J. CULLY, OF MODOC, KANSAS.

IRRIGATION-DAM.

1,356,268.

Specification of Letters Patent. Patented Oct. 19, 1920.

Application filed October 3, 1919. Serial No. 328,169.

To all whom it may concern:

Be it known that I, HENRY J. CULLY, a citizen of the United States, and a resident of Modoc, in the county of Scott and State of Kansas, have invented certain new and useful Improvements in Irrigation-Dams, of which the following is a specification.

My invention is an improvement in irrigation dams.

10 The invention has for its object to provide a dam of the character specified, wherein the dam is arranged to be displaced at the end of a predetermined time by drip controlled mechanism to permit the water 15 to flow freely after a predetermined time.

In the drawings:

Figure 1 is a cross section of an irrigation ditch, showing the dam in use;

Fig. 2 is a perspective view of the drip 20 controlled mechanism;

Fig. 3 is a front view of the drip cup in tripped or released position; and

Fig. 4 is a section, showing the needle valve.

25 In the present embodiment of the invention, a suitable dam is provided, the said dam being in the present instance a sheet of canvas 1, which is adapted to extend across the ditch and the full depth 30 thereof, to check the flow of water through the ditch. At one of its lower corners the dam has an eyelet 2, in which is engaged one end of a flexible member 3, as for instance a rope or cable, and this flexible 35 member passing to the opposite side of the ditch is connected with the trip mechanism for the dam. The said mechanism comprises a tripod 4, which is a table top having three legs, preferably of metal and 40 sharpened so that they may be forced into the ground, as shown in Fig. 1, to properly support the tripping mechanism in a manner to be presently described.

45 This tripod is adjacent to the ditch, and on that bank which is remote from the eyelet 2. The tripping mechanism comprises a cup or casing 5, which is hinged to the tripod, as indicated at 6, to occupy the position shown in Fig. 2 or that shown in 50 Fig. 3. When in the position of Fig. 2, that end of the casing remote from the hinge extends slightly beyond the tripod top and a coiled spring 7 is arranged between the tripod top and the casing, the 55 spring acting normally to press the free end of the casing upwardly, that is acting

normally to move the casing into released position.

A pipe 8 extends transversely of that end of the drip cup which extends beyond the 60 tripod top, and this pipe has an opening at about the center of the drip cup, which registers with an opening 9 in the bottom of the drip cup. Thus water within the 65 casing 5 may flow from the same into the pipe 8 and to a drain cup 10, which is held at one end of the pipe. This opening 9 is a port, with which cooperates a needle valve 11, the said valve being threaded through the top of the drip cup and having a 70 roughened head 12 outside of the drip cup. By means of the valve, the flow of water through the port 9 may be properly regulated.

A spring latch 13 is secured to the under 75 face of the drip cup, in position to engage lightly over the pipe 8, to hold the drip cup until it is well overbalanced by the weight of the water in the drain cup casing 10. The flexible member 3 at the end 80 remote from the eyelet is connected with that end of the pipe remote from the drip cup so that when the pipe swings under the weight of water in the drip cup that corner of the dam remote from the tripod 85 will be lifted to permit the flow of water to displace the dam.

In operation the device is arranged as shown in Fig. 1, and it will be arranged at any desired point within the canal or 90 irrigation ditch, it being held in place by pushing the legs firmly in the ground. The proper amount of water is now placed in the drip cup 5 and the needle valve is regulated to permit the proper flow. When the 95 parts are arranged as shown in Fig. 2, the port 9 of the drip cup will register with the opening in the pipe 8 and the latch 13 will slightly engage the pipe to prevent accidental displacement of the drip cup. 100 When the valve opens at the proper degree there will be a steady flow of water from the drip cup to the drain cup and when the water in the drain cup overbalances the weight of water in the drip cup, the latch 105 will be released, the drip cup will be swung back upon its hinge in which position it is shown in Fig. 3. The pipe 8 will swing upon its hinged connection with the tripod, the said pipe being hinged to the tripod 110 top at the opposite corner from the drip cup.

I claim:

1. In combination with a movable dam for irrigation ditches, of means for moving the dam to permit the water to displace the same, and time controlled mechanism for operating the said means, said time controlled mechanism consisting of a tripod, a drip cup hinged to the tripod and having a valve controlled outlet, a hollow lever hinged to the tripod, said lever being connected with the dam displacement mechanism at one end and having a drip cup at the other, said lever having an opening registering with the port of the drip cup and being normally held from being released by latch mechanism.
2. In combination with a movable dam for irrigation ditches, of means for moving the dam to permit the water to displace the same, and time controlled mechanism for operating the said means, said time controlled mechanism consisting of a tripod, a drip cup hinged to the tripod and having a valve controlled outlet, a hollow lever hinged to the tripod, said lever being connected with the dam displacement mechanism at one end and having a drip cup at the other, said lever having an opening registering with the port of the drip cup.
3. In combination with a movable dam, of means for moving the dam to permit the water to displace the same, a time controlled mechanism for operating the said

means, the time-controlled mechanism comprising a container for water, a support to 35 which the container is hinged to swing, a spring normally acting to move the container in one direction, a counter-weight in the form of a drain cup with which the container communicates, means for controlling 40 communication, said counter-weight being mounted to move downwardly and being connected with the dam displacement mechanism, a latch for normally holding the container against the action of said spring 45 and releasable by the counter-weight.

4. A dam for irrigation ditches comprising a sheet of canvas, means for displacing the sheet, time controlled mechanism for operating the said displacing means, said 50 time controlled mechanism comprising a discharge and a receiving cup mounted to tilt under an excess of water in the receiving cup and connected to the displacing mechanism to operate the same when the 55 cups are tilted.

5. A dam for irrigation ditches comprising a sheet of canvas, means for displacing the sheet, and time controlled mechanism for operating the said displacing means. 60

6. A dam for irrigation ditches, said dam being of flexible material, means for moving the dam to permit the water to displace the same, and time controlled mechanism for operating the said means.

HENRY J. CULLY.
